HIS ATTORNEY.

UNITED STATES PATENT OFFICE.

WALLACE S. CLARK, OF SCHENECTADY, NEW YORK, ASSIGNOR TO GENERAL ELECTRIC COMPANY, A CORPORATION OF NEW YORK.

ELECTRIC HEATING-PAD.

1,015,991.

Specification of Letters Patent. Patented Jan. 30, 1912.

Application filed September 28, 1910. Serial No. 584,222.

To all whom it may concern:

Be it known that I, WALLACE S. CLARK, a citizen of the United States, residing at Schenectady, in the county of Schenectady, State of New York, have invented certain new and useful Improvements in Electric Heating-Pads, of which the following is a specification.

This invention relates to electric heaters and has for its object the provision of a simple and efficient device of this character in which the heating element is concealed within a body of flexible insulating material.

My invention relates more specifically to heating devices, such as electric heating pads and the like. These devices, as ordinarily constructed, are thin flexible bodies having a resistance conductor within them and have been made in various ways, as for instance, by sewing or otherwise attaching the resistance conductor to a body of insulating fabric.

In carrying out my invention, I embed the resistance conductor within a body of water-proof flexible insulating material, such as rubber or the like, so that the conductor will be firmly anchored in place and will be unaffected by moisture.

In the accompanying drawings in which I have shown my invention embodied in concrete form for purposes of illustration, Figure 1 represents a plan view of one form of my device and Fig. 2 is an end view of the same.

Referring to the drawings, 10 and 11 are two sheets of rubber, which I have shown for purposes of illustration as circular in form having projecting portions 12, as shown. Between these two sheets of rubber

40 I secure the resistance conductor 13. This conductor may, of course, be arranged in any desired manner, and may have a thin covering of insulation if desired. For purposes of illustration I have shown the conductor wound in the form of concentric rings. These may consist of wire wound spirally around thin rings of insulation 14, such as mica or the like, although it is obvious that such a support for the wire is not 50 absolutely necessary. In this case, I have shown three of these windings in ring form arranged so as to connect with the lead

wires 15 at the projection 12. The two sheets of rubber, with the windings between them, may be secured together in any desired way, as, for instance, by placing the windings between the two sheets applying suitable pressure and then vulcanizing the two sheets together in a well-known manner. The resulting product is practically a single sheet of rubber with a resistance conductor embedded centrally therein. The conductor is firmly anchored in place so that the parts cannot short circuit on each other or become exposed. Furthermore, the rubber forms a practically air- and water-tight casing around the conductor which is desirable for obvious reasons. It will be seen that I have provided a heating pad which when operated within proper temperature limits will be practically indestructible.

It is quite obvious that various modifications of my invention will suggest themselves to those skilled in the art without departing from the spirit of my invention, the scope of which is set forth in the annexed claims.

What I claim as new and desire to secure by Letters Patent of the United States is:

1. An electric heater comprising a resistance conductor embedded in a body of flexible water-proof insulating material.

2. An electric heater comprising a resistance conductor embedded in a body of flexible rubber.

3. An electric heater comprising two sheets of flexible rubber secured together with a resistance conductor embedded between them.

4. An electric heater comprising a resistance conductor embedded between two sheets of rubber which are vulcanized together.

5. An electric heater comprising a support, a resistance conductor wound thereon, and two sheets of rubber one on each side of the support vulcanized together so as to entirely inclose the support.

In witness whereof, I have hereunto set my hand this 26th day of September, 1910.

WALLACE S. CLARK.
